(57) **CLAIM**

We claim the ornamental design for a display screen with graphical user interface for filtering out optional fields, as shown and described.

DESCRIPTION

FIG. 1 is front view of an animated graphical user interface for a display screen or a portion thereof;
FIG. 2 is a front view of a second image thereof;
FIG. 3 is a front view of third image thereof;
FIG. 4 is front view of forth image thereof; and,
FIG. 5 is front view of fifth image thereof.

The appearance of the image transitions sequentially between the images shown in FIGS. 1-5. The process or period in which an image transitions to another forms no part of the claimed design.

The broken lines showing an electronic device illustrate environmental subject matter, whereas the broken lines showing a display screen and elements of the graphical user interface illustrate portions of the article. No subject matter depicted in broken lines form part of the claimed design.
